FILE

Elwin Theobald, 4631 Solano Way, Fair Oaks, Calif.
95628, and Phillip R. Andrews, 3640 53rd St.,
Sacramento, Calif. 95820

Filed Mar. 29, 1967, Ser. No. 6,423

Term of patent 14 years

(Cl. D37—1)

FIG. 2

FIG. 3

FIGURE 1 is a front perspective view showing our new design for a file;

FIGURE 2 is an enlarged side elevation thereof partially broken away for convenience of illustration; and

FIGURE 3 is an enlarged elevational left end view thereof the sides and bottom of FIGURE 3 being substantially identical in construction.

I claim:

The ornamental design for a file, substantially as shown and described.
